COVERING FOR SURFACES EXPOSED TO
THE WEATHER

Samuel C. Straub, New York, N. Y., assignor to
Certain-Teed Products Corporation, New York,
N. Y., a corporation of Maryland

Application January 23, 1931, Serial No. 510,614

21 Claims. (Cl. 26—5)

This invention relates to covering for surfaces exposed to weather and to methods of applying the same and more especially to units in the form of strips to simulate clapboards and similar wall constructions.

Weather proofing materials in the form of strips or other units cut from sheets and laid in rows in overlapping arrangement have been used in various ways to simulate shingles and similar roof and wall constructions. Shingle simulating strips have also been used in which the strip is divided into sections to simulate the individual shingles by stripes or grooves formed in the coating of asphalt or other mastic material applied to the surface of the sheet. Similarly, coverings for walls have been suggested in which depressions in the mastic coating have been used to simulate the joints of masonry or brickwork. Few, if any, satisfactory suggestions have been made, however, for the simulation of wall constructions such as clapboards or similar siding materials and such suggestions have failed either to effect a proper simulation of the texture and appearance of such siding constructions or have failed to properly provide a protective and weather-proof covering of such character as to resist the action of the elements and to have long life as well as to insure insulation against the loss of heat from the structure and the leakage of air and water thereinto.

One object, therefore, of the present invention is to provide a weather resisting construction which may be laid exposed to the weather and present the appearance of a wood siding construction.

Another object of the present invention is to provide a unit simulating a wood siding material which may be easily applied to the building wall.

A further object of the invention is to provide a clapboard simulating unit of such form that when a plurality of units are applied to the wall the texture and surface character of a wall of wood clapboards would be simulated.

A further aim of the invention is to provide a clapboard simulating unit which may be easily laid to provide the approximately uniform exposure of wood clapboard siding construction.

A further object of the invention is to provide a wood siding simulating construction having high heat insulating as well as weather and water resisting characteristics.

A further aim of the present invention is to provide a method of covering an external surface to produce the constructions which have the features of the present invention.

In one aspect the present invention provides a strip made from a sheet of suitable flexible base which may be impregnated with weather-proof or waterproof material such as asphalt or other bituminous material of a character to easily flex with the sheet. Such strips are usually coated with asphalt or similar material on the side of the strip to be exposed to form a mastic coating to which mineral material such as slate or ground brick or similar granular substances will adhere in order to provide a suitable and pleasing exterior surface resistant to abrasion and the action of the elements and assisting to maintain the waterproofing action of the asphalt coating and therefore of the base felt. Usually such strips have been laid flat upon a roof or wall and their form and surface characteristics have been made such that the simulation of shingles or bricks or other construction units has been produced. The strip of the present invention, however, is of such form and is so made that it may be folded with one portion of the strip reversely lapping upon or covering another portion thereof so that the characteristics of a unit having a thick butt or of tapering cross-section may be simulated. While units of various kinds have heretofore been proposed which have been made of sheets of flexible material folded in various ways, the present invention, while producing the wood siding simulating construction described above and similar constructions to which the invention may be applied, overcomes the difficulties which have been experienced in the use of folded sheets or strips.

It is well-known that when a felt base strip or unit coated with asphalt or other bituminous material and usually surfaced with ground slate or similar mineral material is folded, not only is it difficult or impossible to produce a fold in a substantially straight line, which is usually desirable or requisite, but as in general the fold causes one lap to be more or less sharply reversed upon the other, a cracking of the asphalt coating occurs and a separation of the mineral materials along and adjacent to the fold is produced since, even though a relatively thin felt is used and the attempt is made to apply a thin coating of asphalt or other mastic material a thickness of the coating and of the strip of substantial degree is built up, and it becomes difficult or impossible to prevent the cracking.

While heretofore it has been suggested to assist the making of the fold in a straight line by scoring the sheet or the asphalt coating, such a method is not always possible and does not pro-

duce satisfactory results. Such scoring methods merely squeeze a small amount of the asphalt or mastic coating on the felt along the line of the score or compress the coating further into the 5 felt and do not sufficiently relieve the tension which exists in the asphalt coating upon bending and flexure. Asphalt and other mastic compounds while flexible and having other necessary qualities are not sufficiently elastic to withstand 10 this tension when a substantial thickness is subjected to a relatively sharp bend (180°). The resulting cracking produces the undesirable results described.

A further feature of the present invention, 15 therefore, is to provide for the removal of a portion of the asphalt coating adjacent or along the line of the fold or to otherwise reduce the thickness of the asphalt coating along the fold so that the tension is relieved in the portions adjacent 20 to the line of the fold and thereby cracking is prevented. In the units of the present invention this folding may be done to such degree that the bend is made at sharper angles than would otherwise be possible and the folds may be bent upon each other to substantially 180°. 25 One method of providing for the reduced thickness of the asphalt coating is to form a scraped groove in said coating according to the method disclosed in the patent to Outman, No. 1,426,497, 30 in which, by means of a scraping device the asphalt is removed from the area to which the scraper is applied to form a partially coated groove or area of substantially reduced thickness but of weather-proofing character. This scraped 35 surface may also provide a relatively hard, smooth area to which the mineral material used for surfacing will not readily adhere. It will be seen, therefore, that the tension in the asphalt layer is, by this method, easily reduced or eliminated 40 when the fold is made and further that a groove or area having different characteristics than the main coated surface of the strip is provided. These characteristics are utilized in special ways as hereafter described. While the provision 45 of a groove or area having a reduced thickness of asphalt coating is preferably accomplished by the method according to the Outman Patent 1,426,497, other methods for removal of the asphalt or of preventing its application may be used within the scope of the present invention to produce the desired result.

When a strip of suitable base material such as impregnated felt is coated with a layer or coating of asphalt or other mastic material and a 55 groove or area having a reduced thickness of coating is provided, as just described, the remaining surfaces being suitably coated with surfacing material to represent the exposed surface of a construction such as clapboards of wood, 60 there is provided a unit which may be easily handled in suitable lengths and readily packed and shipped. In applying such units to the wall or other supporting structure, the unit may be placed with the mineral surfaced side next to the supporting structure, and the portion on the side 65 of the groove opposite the area to be exposed may be fastened to the structure by any suitable means such as nailing. The strip may then be bent or folded reversely upon itself along the 70 line of the groove or in the area of reduced thickness of coating near or adjacent the edge of the mineral surfaced area. Usually the portion applied to the wall as just described will be of less width than the portion providing the mineral 75 surfaced area to be exposed. The edge of said

mineral surfaced area remote from the groove or area of reduced thickness of the asphalt coating may then be fastened to the structure by suitable means. Due to the slight stiffness of the otherwise flexible felt of the strip a perfectly flat fold is usually not produced but a thickness of greater or less degree such as is usual with clapboards of wood materials is provided in the wood siding simulating strip of the present invention. The amount of this thickness of the "butt" may be controlled by greater or less thickness of the felt or of the asphalt coating or the amount of material removed from the scraped portion or combination of these factors as well as by the degree of bending above referred to. The width of the groove may also be varied in order to modify the effect of this simulation of thickness of "butt".

A further feature of the invention in the use of a groove or area from which the slate or mineral surfacing material has been removed or to which it does not adhere is provided by the effect of shadow which such a groove or area may be caused to give. It has been found that the bending or folding of the strip along the line of the groove or area of reduced thickness of asphalt may be so done that said groove or area is in somewhat convex form and a small width of the surface thereof is visible when the strips are applied to a wall surface. This effect may be increased or decreased by the removal of less or more asphalt coating from the groove alone or in combination with the use of a greater or less thickness of felt. Such shadow effect therefore constitutes one of the features of the present invention.

It is further to be noted that the provision of a groove or area of reduced thickness of asphalt, especially when formed by the method of the above mentioned Outman patent, No. 1,426,497, produces a more sharply defined edge for the mineral surfaced area of the strip which is to be exposed. This feature further assists in the simulation of clapboard constructions of the usual type made of wood in which the clapboards are planed to sharp edges.

The covering units of the present invention are particularly adaptable to simulate constructions such as wood clapboard siding construction in which a substantially uniform width of exposure is provided with a substantially uniform thickness of butt and of taper of the section. While the invention is not limited to units of uniform dimensions and arrangement of the portions of the strip relative to each other, a particular feature of the present invention lies in the provision of units of substantially uniform width having grooves or areas of reduced thickness of mastic coating of substantially uniform dimensions and placed in substantially uniform relation to the edges of the strips and the surfaces to be exposed. There is thus made possible an easy 135 method of application of the strips to the wall or other supporting structure which obviates the use of measurements in order to insure substantially uniform "lay up" of the siding upon the structure. With the units of the present invention which are adapted to be folded while laying in place upon the structure, it is possible to match the edge of the strip to be laid relative to the strip already laid, the spacing of the strips and the amount of exposure being determined by the folding along the line of the groove or the edge of the mineral surfaced exposed portion which is adjacent to said groove or area of decreased asphalt thickness. There therefore is included in 150

the present invention the method of laying strips of the character herein disclosed in order to provide a covering simulating constructions of wood or other materials having a substantially uniform exposure of its units or elements laid in overlapping arrangement upon a supporting structure.

A further feature of the present invention lies in the provision of a construction having high heat insulating quality. As will be understood from the above discussion, and particularly from the description in connection with the drawing, the folded strip provides an air space between the supporting structure and the outer exposed portion of the strip. This air space is of a thickness varying from the thickness of the butt to nothing where the upper edge of the unit is attached to the supporting structure. It will be seen, however, that successive cells or isolated volumes of air will be contained in the space behind the strips when applied in overlapped arrangement upon the structure. It is well-known that such isolated and confined air volumes provide high heat insulation. Such insulation is maintained if circulation of the air through such spaces is prevented. It will be seen from the figures in the drawing that the construction provided by the strips applied to the structure prevents passage of the air from the volume behind one strip to the volume behind the adjacent strips above and below upon the structure. In order to obviate leakage of air around the ends of the strip, the present invention proposes to interlock the strips which are adjacent to each other in a row upon the structure as will be illustrated and described in connection with the drawing. Other means may be used at special points in the structure to meet special conditions to prevent the circulation of air. Such means, however, are included within the present invention which broadly aims to provide a construction formed of covering strips of the type described, arranged so as to provide cellular spaces to afford a heat insulating construction.

Other features and objects of the present invention will appear from a consideration of the following description taken in conjunction with the accompanying drawing in which

Fig. 1 is an assembly of units in overlapping arrangement.

Fig. 2 is a cross-section on line 2—2 of Fig. 1.

Fig. 3 is a face view of a single covering unit.

Fig. 4 is a cross-section of Fig. 3.

Fig. 5 is a cross-section of the assembly of units shown in Fig. 1 taken on line 5—5.

Fig. 6 is an enlarged cross-section of the strip adjacent the groove.

Fig. 7 is a cross-section showing a modified embodiment of the invention.

In Fig. 1 the units 1 are shown laid endwise to each other in rows with one row lapped upon another. The ends of the units are also in lapped arrangement in relation to the units adjacent in the row. The portion 2 of the unit has been folded reversely in relation to the portion 3 which forms the exposed face of the unit. The portion 4 extending beyond the face portion 3 constitutes an edge portion upon which is lapped the reversely folded portion or flange 2 of the unit. In the assembly arrangement shown in Fig. 1 the folds in the units have been made along the groove 5, a portion of the surface of which may be seen in the assembly view due to the somewhat rounded form as a result of the bending of the strip to form the unit. The exposed area 3

of the units has been suitably surfaced, for example with granular mineral material, and this surfacing may extend over the area 4 which is overlapped by a superimposed unit. The flange 2 as shown in the figure is similarly surfaced with mineral material although this surfacing may in some cases be omitted.

The units in the form illustrated in Fig. 1 are formed from strips all of substantially the same width and the groove has been formed in the surface thereof at substantially the same distance from the longitudinal edge of the strips in all units. In the folded form, therefore, the flange 2 is of substantially a uniform width and the face portions of the units are also of substantially the same width. It will be seen from Fig. 1 and also by reference to Fig. 2 showing the section of the assembly arrangement that the edge of the flange is substantially matched with the edge of the face portion of the unit in its folded form. It will therefore be clear that the exposed portion 3 of the face of the unit is determined by the lap of the flange 2 upon the portion 4 of the face of the unit next beneath, and that therefore a substantially equal exposure is obtained for all the units and rows of units when so assembled. While such uniformity of dimension is not necessary in all cases, and the present invention is not limited to the uniform construction shown in Figs. 1 and 2, yet this construction shows a preferred embodiment of the invention and one which has the advantages of uniformity of the strips from which the units are made, thereby reducing the cost of manufacture and assuring uniform surface characteristics, and also reducing the cost of applying the units to the wall or other structure. The ease of laying the units upon the surface to be covered will be evident since it is only necessary to align the edge of the flange 2 substantially with the edge of the face portion 3 of the unit beneath which has previously been laid, thereby insuring the position of the strip or unit being laid relative to the strip beneath. No measurements are necessary to effect the proper placing of the units and rows one relative to the other. When the strip has been folded along the line of the groove 5 and the face portion 3 has been folded over the flange 2 and fastened to the supporting structure, it will be evident, by reference to Figs. 1 and 2, that the upper edge of the face portion of the unit being laid will fall into a substantially definite position since the groove has been formed in the strip at a predetermined distance from said upper edge.

The units in their folded form and preferably of like dimensions have a cross-section at their lower or butt portion which is of U-shape. It will be seen that therefore the units may be lapped endwise so that the U section of one unit lies within the U section of the strip adjacent endwise thereto. A consideration of Fig. 1 in connection with Fig. 5 will make plain that there is complete overlapping of the endwise adjacent end portions of adjacent strips. There is thus provided a complete sealing of the assembly of units against entrance of water or wind and the water tight construction is thus built up due to the endwise overlapping and interlocking as well as the overlapping of the units in their folded form in this manner and shaped after the manner of wood clapboards. These endwise joints or laps 6 may be staggered relative to each other to more effectively seal and prevent water finding a continuous joint through which it may seep. The endwise overlapping further provides the closure of

the cell-like space which is formed behind the face portion of the units and which constitutes a confined space when the flanges 2 and the upper edges of the face portions 3, 4 have been suitably fastened to the supporting structure or wall. If desired, the end lapped portions 6 may be suitably cemented or otherwise fastened to assist in maintaining tight end joints.

It will be noted that the groove 5 has a somewhat convex surface as mentioned above and shown in Fig. 2. While, due to the scraping process by which these grooves are preferably formed as above described, they have a sharply defined edge 7 and thereby provide the face portion of the unit which is to be exposed with a relatively sharp and substantially rectilinear edge to carry out the simulation of the clapboard, the slightly convex surface of the grooves being usually also of contrasting color is partially visible when the assembly upon the structure is viewed at a distance under the usual circumstances. This partially visible area or line of the groove gives the appearance of a shadow and thus assists in simulating the effect produced by the clapboard and similar constructions. The degree of this shadow effect may be varied as desired by increasing the width of the groove, its convexity, and the amount of its area caused to be visible.

In the units usually used for the purpose of the present invention strips of roofing felt impregnated with bituminous material such as asphalt and having a coating of such bituminous material thereon are provided with a groove scraped in the bituminous coating, the remaining portions of the coating being surfaced with a suitable mineral material such as slate. Fig. 3 shows a face view of such a strip in which the groove is shown at 5 and the slate covered face portion of the strip at 3 and the portion to be used as a reverse flange is shown at 2. Similar reference characters designate the portions of the strip in Fig. 4 in which also the base material or roofing felt is shown at 8, the asphalt coating at 9 and the mineral material applied to the asphalt coating at 10. It will be noted from the section in Fig. 4 that a slight amount of the asphalt coating remains at the bottom of the groove. In the scraping process according to the patent to Outman No. 1,426,497, due to the character of the asphalt applied as a coating and its adhesion to the felt a thin layer or film of the asphalt remains in the groove and this serves as a protection to the felt beneath and as a weather proof and water tight coating. It will be clear from Fig. 4 and Fig. 6, showing an enlarged section of the strip adjacent the groove, that the reduction of the thickness of the asphalt coating 9 to the thickness of this thin layer or film in the groove makes it possible to bend or flex the strip and the asphalt impregnated felt base 8 without causing extreme tension in the asphalt coating 9 on either side of the groove. It is therefore possible to avoid the cracking of the asphalt as described above and the separation of the slate granules of the surfacing due to this cracking when the strip is folded to form a unit.

It will be apparent from a consideration of Figs. 3 and 4 in connection with the remaining figures that strips may be shipped flat, thus providing a convenient package when not in long lengths. It has been found, however, that a convenient package for shipment and for handling in applying the strips may be made by forming a roll of a continuous long length of the strip.

This roll will then be of a width equal to the width of the strip from the edge of the flange to the edge of the face portion. In a practical embodiment of the invention such a strip might be 9 inches wide, making the width of the roll 9 inches. In manufacturing these strips according to the Outman process in a machine, four strips at a time may be made, being cut from a sheet 36 inches wide. The grooves, for example of a width of $\frac{1}{4}$ inch, might be so placed relative to the edges of the strips as they are slit apart that the width of the flange would be $1\frac{3}{4}$ inches. Further, it has been found advantageous in some cases, in shipping such rolls, to wind the four lengths on a single shaft or mandrel so arranged that the strips may be unrolled each one independently of the other. The arrangement may, however, be made so that all four strips are unwound together. Such a form of package makes possible the application of the strips or stripping in unbroken lengths to the side walls of a building, for example, thereby avoiding endwise joints. In practice either or both methods of assembling the strips or stripping preparatory to application upon the structure, i. e., as flat units or in rolls, may be used.

Such shipment in strips or in rolls as desired is made possible by the present invention because of the feature thereof which permits bending of the strip as applied to the structure without cracking of the coating or surfacing material as described above. It is therefore possible to apply the strips or stripping to a structure under adverse weather conditions and particularly when the temperature is much lower than is possible if the scraped groove were not formed in the strips. Not only is it therefore possible to avoid preforming the strips in order to prevent the cracking, but being provided with a groove or scraped portion it is unnecessary to heat the strip on the job before bending, which method would become necessary if strips without such grooves were shipped flat or in rolls for convenience of shipping and then bent or folded upon application to the structure. Furthermore, since it is possible to bend the units or stripping of the invention upon application to the structure, a more secure method and arrangement of fastening by nailing or otherwise can be provided than with preformed units.

In applying the strips or stripping to the structure various methods may be used, but I have found that certain advantages are obtained by the particular method I now describe. According to this method the units or the lengths of stripping may be applied to the wall or supporting structure by placing the strip or stripping against the wall with the mineral surfaced side next thereto. The flange portion 2 is then suitably fastened to the wall, for example, by driving nails 11, Figs. 1, 2, 7, through this flange from the back side of the felt, holding the face portion of the flange against the wall. When the flange portion of a strip has been suitably fastened to the wall with the flange portion uppermost and the mineral surfaced side toward the wall as just indicated, the portion 3 of the strip may be lifted and folded upwards and over the flange portion by bending the strip in the groove 5. Such flexure, due to the residual stiffness of the felt, will cause the portion 3 of the strip to stand away somewhat from the flange portion 2. There will thus be formed the butt edge of a unit such as a clapboard having a thicker portion at said butt end than in the remaining portion of the unit. When the free edge of the face portion of the unit is simi-

larly fastened to the wall or structure an approximately triangular form of cross-section of the unit is produced or one which corresponds to the section of a clapboard or similar type of covering material, such as novelty siding.

The nails 11 are completely covered by the folded-over portion of the unit and the nails which are driven in the free edge portion of the face of the strip are likewise covered when the next super-imposed unit is similarly laid. The unsightliness of the nails or other fastening devices is thereby avoided and they are properly protected against the action of the weather. The nails driven through the flange portion 2 when the strip is first applied to the structure need only be sufficient in number to hold the strip or striping in place while the face portion is bent or folded thereover. It will be clear from a consideration of the drawing and the description of the method of application that in addition to the nails driven through the edge of the face portion of the unit to secure said edge portion of the face of the clapboard simulating unit, the nails driven through the superimposed flange of the next strip will also hold this upper edge of the face portion. By suitable spacing of the nails as driven through the upper edge portion of the face of the unit or strip the subsequent nailing of the flange applied thereover will provide adequate fastening of the upper edge of the face of the unit in order to sustain the weight of the strip and hold it in place. There is thereby secured an economy in the use of nails or other fastening devices and at the same time a close fitting application of the units to the structure with the resultant prevention of air leaks is secured.

It will be seen from a consideration of the figures that a space enclosed between flange 2, the face portion 3 of the strip and the wall or supporting structure forms a somewhat triangularly shaped cell in which air is enclosed without opportunity for free passage from one cell to the next. When the lapping of the units at their ends is effected in the manner above described, a continuous space or cell 15 is formed behind the clapboard simulating unit which, since it encloses a confined volume of air, constitutes an effective heat insulating unit, it being well known that such confined volumes of air afford one of the most efficient means of insulation which are known. By suitably closing the ends of each cellular space in the row and, if necessary, dividing the space endwise by suitable inserts therein, passage of the air endwise along the cell may be prevented.

While the invention has been illustrated to simulate the clapboard construction, its various features are not limited to such specific construction, and its advantages may be obtained in units simulating other types of construction where it may be applied. Various modifications may be made within the scope of the invention. For example, the groove 5 may be varied in width as suggested above and may be extended to include the width of the flange. The mineral surfacing material may be omitted from the flange or other portions of the strip and various types of materials may be used to provide the flexible base or the coating or the surfacing material. Various widths of strip may be used to form the units and various modifications of the relation between the groove and the flange may be made. Instead of the lapped construction shown in Fig. 1 for the end joints of the strips, a butt joint may be made with or without a suitable strip or a suitable filler at the joint

to effect the mechanical cooperation of the strips.

The surfacing material may be varied in color or thickness or granular character or may be omitted altogether in order to produce certain effects to simulate sidings painted in different colors or units of different characters and textures. The color and surface character of the groove may be varied by the use of different coatings applied thereto such as fine slate or mica or other material, and combinations of these for varying the character of surface may be combined with the variations described above to produce a different character of butt or form of cross-section or degree of curvature of the surface of the groove or of the exposed surface of the strips or units. By suitable bending or pre-forming the strips, units to simulate novelty siding may be produced.

While the uniformly dimensioned strips which have been described above to produce a siding construction of uniform spacing offer many advantages, a construction as shown in Fig. 7 may be utilized under some conditions. While not providing the self-spacing feature which the construction described in connection with Figs. 1, 2 and 5 affords, the construction illustrated in Fig. 7 makes possible the pre-forming and folding of the clapboard or siding simulating units. By such pre-forming it is possible to produce a more exact shape of the clapboard or siding and to incorporate mechanical fillers or other features if desired. This construction also offers the advantage that the units may be completely closed to form individual cells, using cement to seal and bind the laps if desired, thus providing a highly efficient insulating unit. While the units illustrated in Fig. 7 may be pre-formed as just described, they may also be applied to the wall or structure by the method described in connection with Figs. 1, 2 and 5. In such case the method of nailing may be used which is described in connection with these other figures, thus securing an especially firm fastening for the lower portion of the units. In such pre-folded and pre-formed units in some cases the scraping of the groove or the removal of the asphalt material may be dispensed with and other methods or means adopted to produce the triangularly sectioned air cell enclosing folded unit. Such methods and such forms of celled siding strips or units are included within the present invention.

Having now described my invention, I claim—

1. A strip of asphalt impregnated felt coated on one side thereof with asphalt, having a groove scraped in said asphalt coating lengthwise of said strip to provide a residual coating only of said asphalt in said groove, said groove dividing the surface of the strip into two unequal areas, the portion of the strip of lesser area being so folded upon the portion of greater area that the groove is external to the fold, said groove being so formed that the edges thereof sharply demarcate said areas from said groove, said fold being made so that said edges of said groove define the edges between the faces of the folded strip and the butt end thereof formed by the surface of the groove.

2. A clapboard simulating element comprising a strip of felt impregnated and coated on at least one surface with asphalt, said strip having a groove scraped with sharply defined edges in said coating lengthwise of the strip to a thickness substantially less than the thickness of said coating as applied, said groove having a width

simulating the thickness of the butt edge of a clapboard, said strip being folded in said groove to leave the groove external to the fold, and to form the butt edge of the simulative clapboard between said edges of the groove, said edges defining the edges of the simulated clapboard.

3. A covering for building walls to simulate clapboards comprising a plurality of asphalt coated and mineral surfaced roofing strips each folded along a groove having sharply defined edges and formed in the asphalt lengthwise of the strip to divide the exposed clapboard surface from a reverse unexposed flange, each flange being lapped upon the upper portion of the strip beneath and fastened to the wall with the fastenings covered by the portion of the strip to be exposed, said grooves having a width defining the bottom shadow forming butt edge of the simulative clapboard, said edges of the groove defining the edges between said butt edge and the faces of the clapboard.

4. A covering unit for exposure to the weather, comprising a base, and a mastic coating applied on said base, a substantially square edged groove in said coating having the thickness of the coating therein on said base reduced by removal of a substantial part of said applied mastic coating, said unit being folded along said groove to form the butt end of said unit and to provide a reverse portion covered by the remaining portion folded thereover, said square edges of said groove forming the edges of said butt end of the unit.

5. A covering to simulate clapboards, comprising a plurality of similarly dimensioned strips of flexible material coated with a layer of mastic material, each strip having a groove lengthwise thereof formed in said mastic layer and similarly located in each strip at a predetermined distance from each edge of said strip, said groove having a width simulating the thickness of the exposed edge of a clapboard, the thickness of the mastic layer in said grooves being less than that of the adjacent areas of the layer, said strips each being folded in said groove to form a reverse flange folded upon the portion of the strip on the opposite side of the groove, said strips being placed in overlapping arrangement with the lengthwise edge remote from the groove of the reverse flange of a superimposed strip substantially matching the lengthwise edge remote from the groove of said portion of a subjacent strip on the opposite side of the groove from the flange of said subjacent strip, said reverse flanges being lapped upon the portions of the subjacent strips adjacent said edges thereof remote from the grooves on the opposite side of the grooves from the flanges, said portions of the strips on the opposite side of the groove from the flange being partially exposed and partially extending under the reverse flanges of the superimposed strips.

6. A covering to be exposed to the weather upon a supporting structure, which comprises a plurality of units in overlapping arrangement each composed of a flexible base coated with mastic material having a depression in said coating separating a portion of the strip to be partially exposed from a portion thereof providing, when the unit is folded along said depression, a reverse flange, said depression having a width approximating the desired thickness of the butt of the unit and having edges sharply demarking said depression from said portions separated by said depression, said reverse flange portions being lapped upon those portions of the units next be-

neath which are adjacent the edges thereof to be overlapped, and means for concomitantly fastening to the structure said flange portions and said overlapped portions, the flanges and fastening means being covered by the portions of the strip to be exposed and folded thereover, the coating in said depressions being of less thickness than that upon said exposed portions and upon said flanges, said exposed portions and said flanges being so folded in relation to said depression as to provide the thickness of the butt of the units, said edges of said depression defining the edges of the butts of said units.

7. The method of covering a surface with a plurality of similar covering units in overlapping arrangement, each of said covering units being formed of a flexible base having a coating of mastic material on at least one surface thereof, said coating being of less thickness along a channel formed in the coating than the thickness of the areas of the coating adjacent to the channel, said channel being located in predetermined relation to two edges of the unit extending generally in the same direction as the channel, said channel being of predetermined width, which comprises placing a unit with the coated surface next to the surface to be covered, fastening to said surface to be covered the portion of the unit on one side of the channel, folding said base in said channel to form the butt of the covering unit as determined by the width of said channel and to fold upon said fastened portion of the unit the portion of said unit on the opposite side of the channel from said fastened portion so as to cover said fastened portion while exposing the coated portion on the opposite side of the channel from said fastened portion, matching with the edge of said exposed portion remote from the channel the edge remote from the channel of the portion to be fastened of a similarly placed similarly channelled second unit and similarly folding said second unit in said channel to determine the exposure of said first unit.

8. The method of covering a wall to simulate a plurality of siding elements in overlapping arrangement which comprises placing a horizontally extending flexible strip suitably coated and surfaced with its surfaced side next to the wall, said coating having a depression therein lengthwise of the strip in the upper portion thereof as placed upon the wall, said depression being located in a predetermined position with respect to the lengthwise edges of said strip and being of predetermined width and depth, fastening to the wall said upper portion of the strip as so placed, folding the strip in a lengthwise fold along said depression to form the butt end of the siding element as determined by said depression and so as to reversely fold over said fastened portion the other portion of the surfaced side of the strip, similarly placing a second similar strip with the upper edge of the strip as so placed substantially matching with the upper edge of the reversely folded portion of the strip beneath, and folding said second strip along a similar depression similarly located in the coating of said second strip lengthwise thereof, whereby a predetermined exposure of the simulative siding elements and a predetermined form of their butt ends is obtained.

9. A covering unit to simulate a siding element, comprising a base of flexible weather resisting material folded in two with one folded portion substantially equal to and folded upon the other

folded portion to form a free space therebetween, the fold being formed with appreciable thickness to simulate the butt end of the siding element.

10. A covering to simulate an assembly of siding elements comprising a plurality of covering units in overlapping arrangement, said units being formed of a base of flexible weather resisting material folded in two with one folded portion substantially equal to and folded upon the other folded portion and providing a fold of appreciable thickness to simulate the butt end of the siding element, said units being lapped with the butt simulating edge overlapping the two folded edges and secured in relation thereto by a single fastener passing through at least one folded portion near said fold and through both overlapped folded edges of the subjacent unit.

11. A covering element comprising a base in the form of a strip of flexible material having a mastic coating on at least one side thereof, a portion of said coating upon an area of the strip extending longitudinally thereof being of less thickness than that upon an adjacent area of the strip, said two areas meeting along a line extending longitudinally of the strip and providing by the difference in thickness of their coatings a shoulder along said line of meeting of said areas, said strip being so folded upon itself in said area of less thickness of coating adjacent said shoulder that the side of said strip having the coated areas thereon is external to the fold, said fold being so made in relation to said shoulder that the external surface of the folded edge forms the butt end surface of the covering element and the shoulder provides the edge between said butt end surface and the surface to be exposed of the covering element.

12. A covering element comprising a base in the form of a strip of flexible material having a mastic coating on at least one side thereof, a portion of said coating upon an area of the strip extending longitudinally thereof having a surface and a form produced by scraping said coating to a less thickness than that upon an adjacent unscraped area of the strip, said two areas meeting along a line extending longitudinally of the strip and providing by the difference in thickness of their coatings a shoulder along said line of meeting of said areas, said strip being folded upon itself in said scraped area with the said areas external to the fold and in such relation to said shoulder that said unscraped area forms the face to be exposed of the covering element and the portion of the scraped area adjacent said shoulder is formed as the butt end surface of the covering element, said shoulder forming the edge between said butt end surface and said face to be exposed.

13. A covering element comprising a base in the form of a strip of flexible material having on at least one side thereof a mastic coating capable of binding to said base granular surfacing material of given grain size, a portion of said coating upon an area of the strip extending longitudinally thereof being of a thickness sufficiently reduced substantially to prevent a layer of said granular surfacing material adhering thereto, said area of reduced thickness of coating being adjacent to and meeting in a shoulder along a line extending longitudinally of the strip an area of normal thickness of coating having adhering thereto a layer of said granular surfacing material to provide the face to be exposed of said element, said strip being folded upon itself in said area of reduced thickness adjacent said

shoulder with said areas external to the fold and with the width of the external surface of the folded edge measured from said shoulder substantially equivalent to the thickness of the butt end of the covering element and with said shoulder forming a sharply defined edge between said butt end and said mineral surfaced face to be exposed of said element.

14. A covering element comprising a base in the form of a strip of flexible material having a mastic coating on at least one side thereof, said coating having formed therein a groove extending lengthwise of the strip and forming with respect to the area of the strip on at least one side of said groove a shoulder extending lengthwise of the strip sharply demarking said area from said groove, said strip being folded in said groove with said groove and said area external to the fold and with the width of the groove determining the width of the external surface of the folded edge of the element to form the butt end of the covering element, said area forming the face to be exposed of the element and said shoulder forming the edge between said butt end and said face of the element.

15. A covering element comprising a base of flexible material in the form of a strip having parallel longitudinal edges and having a mastic coating on at least one side thereof, said coating having formed therein a groove extending parallel to said edges and separating said coating into two areas at least a portion of one of which areas adjacent said groove is intended to be exposed, said groove providing parallel shoulders sharply demarking said areas from the surface of said groove, said strip being folded in said groove with said groove and said areas external to the fold and with the portions of the base of said strip bearing said areas folded one upon the other, said fold being made between said shoulders to form the butt end of the element as determined by the width of said groove and with said shoulders respectively forming the edges between said butt end and the face to be exposed of said element and between said butt end and the area upon said other folded portion of the base, said other portion of the base providing a reverse flange for fastening the element to a supporting structure.

16. A covering element comprising a base of flexible material in the form of a strip having parallel longitudinal edges and having a mastic coating on at least one side thereof, said coating having formed therein a groove extending parallel to said edges and separating said coating into two areas at least a portion of one of which areas adjacent said groove is intended to be exposed, said groove providing parallel shoulders sharply demarking said areas from the surface of said groove, said strip being folded in said groove with said groove and said areas external to the fold and with the portions of the base of said strip bearing said areas folded one upon the other, said fold being made between said shoulders to form the butt end of the element as determined by the width of said groove and with said shoulders respectively forming the edges between said butt end and the face to be exposed of said element and between said butt end and the area upon said other folded portion of the base, said other portion of the base providing a reverse flange for fastening the element to a supporting structure, the width transversely of said groove of the portion of the base bearing said area to be exposed being greater than the width trans-

- versely of said groove of the portion of the base providing said reverse flange, the difference between said portions substantially determining the exposure of the face to be exposed of said element. 80
17. A covering element comprising a sheet of flexible material capable of being formed by folding and folded in two with one folded portion folded upon but free of mutually supporting bearing upon the other folded portion throughout a major portion of their common extent, the fold being formed with appreciable thickness as the butt of the covering element and with at least one sharply defined edge formed in the fold of the sheet as the edge between the end surface of the butt and a face surface of the element provided by one of the folded portions. 85
18. A covering element comprising a sheet of flexible material capable of being formed by folding and folded in two with one folded portion folded upon but without mutually supporting bearing upon the other folded portion throughout a major portion of their common extent, the fold being formed with appreciable thickness as the butt of the covering element and with sharply defined edges formed in the fold of the sheet as the edges between the end surface of the butt and the face surfaces of the element provided by the folded portions. 90
19. A covering element comprising a base of flexible material in the form of a sheet having a mastic coating on at least one side thereof, said base being capable of being formed by folding and of retaining thereon in the folded form said mastic coating, said sheet being folded in two with one folded portion folded upon the other 95
- folded portion and so as to form a free space between said folded portions, the fold being formed with appreciable thickness as the butt of the covering element, said coating in the folded form upon said base being of such contour that a sharply defined edge is provided between the end surface of the butt and a face surface of the element provided by one of the folded portions. 100
20. A covering element comprising a sheet of flexible material capable of being formed by folding and folded in two with one folded portion folded upon the other portion, the fold being formed with appreciable thickness as the butt of the covering element to form a cell-like space between said folded portions and with a sharply defined edge formed in the fold of the sheet as the edge between the end surface of the butt and a face surface of the element provided by one of the folded portions, said edge coinciding with a shoulder formed by a depression in the sheet. 105
21. A covering element comprising a base in the form of a strip of flexible material having formed in a face thereof a groove extending lengthwise of the strip and forming with respect to the area of the strip on at least one side of said groove a shoulder extending lengthwise of the strip sharply demarking said area from said groove, said strip being folded in said groove with said groove and said area external to the fold and with the width of the groove determining the width of the external surface of the folded edge of the element to form the butt end of the covering element, said area forming the face to be exposed of the element and said shoulder forming the edge between said butt end and said face of the element. 110
